CAP FOR COLLAPSIBLE TUBES

George W. Temple, New York, N. Y., assignor to
 Victor Metal Products Corporation, Brooklyn,
 N. Y., a corporation of New York

Application June 12, 1937, Serial No. 147,849

2 Claims. (Cl. 221—60)

This invention relates to caps for containers and the like and particularly to the screw caps for collapsible tubes.

Difficulty has been experienced in the past with collapsible tubes for the reason that the user is apt to put the cap on the neck of the tube in slightly angular position instead of coaxially with the tube, with the result that on screwing the cap into place, the threads on the tube neck, or sometimes even the internal threads of the cap are crossed and stripped. Another difficulty has been the accumulation inside of the cap and its threads of excess or unused pasty material exuding from the tube if such material is not entirely removed before the cap is screwed on.

My invention therefore contemplates the provision of pilot means on the cap to center and align the cap coaxially with the tube preparatory to the engagement of the screw threads of the cap and neck thereby to insure the proper positioning and engagement of said threads when the cap is rotated and eliminating the danger of the threads being stripped or crossed.

25 My invention further contemplates the provision of pilot means on the cap which not only automatically centers and aligns the cap on the neck of the tube, but also disposes of any excess pasty material at the end of the tube.

30 The various objects of the invention will be clear from the description which follows and from the drawing, in which,

Fig. 1 is a partial elevation and partial vertical section of my new cap as it appears applied to a tube preparatory to screwing it into place to seal the tube.

Fig. 2 is a similar view of the same showing the cap screwed into its tube-sealing position.

Fig. 3 is a similar view of a modified form of the cap wherein the pilot means is made hollow.

In the practical embodiment of my invention which I have shown by way of example, the usual collapsible tube 10 is provided, on the reduced neck 11 of which are cut the external screw

45 threads 12. Said threads terminate a considerable distance below the top surface 13 of the neck thereby providing a terminal cylindrical unthreaded surface 14, the diameter of which is the same as that of the base of the threads 12.

50 The sealing cap 30 may be of any desired shape having a top portion and a depending skirt portion 15 and is provided with the annular recess 17 concentric with the skirt portion for the reception of the neck 11 of the tube. The outer wall of said recess 17 is provided with the usual

internal screw threads 16 adapted to fit and engage the threads 12 of the neck.

Integral with the top part of the cap and concentric with the skirt portion, is the pilot member 19, the substantially cylindrical wall 5 of which forms the inner wall of the recess 17. The lowermost end part 20 of said pilot member is preferably in the same plane as the lowermost edge 21 of the skirt portion of the cap, and is preferably rounded convexly. The pilot member 19 preferably tapers slightly to a somewhat greater diameter at its upper end to permit the lowermost end thereof to be readily inserted into the neck opening 22 of the tube. Adjacent its uppermost end, that is, where it joins the remainder 16 of the cap, the pilot member is provided with an upwardly and outwardly tapered conical surface 23 merging with the top portion of the cap and adapted to engage the circumferential edge 24 of the neck opening 22 and to seat thereon when 20 the cap is screwed into place (Fig. 2) and thereby to seal said opening.

To assemble the cap on the neck, the pilot member 19 is initially inserted into the neck opening 22 of the tube and at the same time the cap 25 is moved downwardly to carry said pilot member as far into the neck as it will go. Said member 17 being very nearly of the same diameter as that of the neck opening, prevents any material tilting of the cap relatively to the tube. At the same 30 time, the internal threads 16 of the skirt portion of the cap slide over the unthreaded part 14 of the neck until they engage or contact with the uppermost of the threads 12. When such contact or engagement takes place, it must occur in the 35 accurately centered position in which the cap is maintained and set by the pilot member, whereafter rotation of said cap will screw the cap on to the tube in its proper position until the conical portion 23 engages the edge 24. It will 40 be understood that when the pilot member 19 is first freely inserted into the neck opening, any pasty material which lies above or adjacent the top of the neck opening is pushed back into the 45 tube by said member, and is thereby prevented from reaching or passing out of the recess 17.

In that form of the invention shown in Fig. 3, the pilot member 30 is preferably made hollow, being provided with a suitable preferably central 50 recess as 31. By the provision of said recess, it will be understood that less material is needed to form the cap, while at the same time less resistance is offered to the initial entrance of the pilot member into the tube opening, since part 55

of the pasty material at the end portion of the tube may enter said recess 31.

It will be seen that by the provision of pilot means for guiding the cap into its proper initial position in which the threads thereof are ready to engage the corresponding threads of the neck, adequate means are provided for insuring the proper positioning and sealing action of the cap on the tube even though it is attempted to assemble these parts more or less carelessly.

10 While I have shown and described certain specific embodiments of my invention, I do not wish to be understood as limiting myself thereto, but intend to claim my invention as broadly as may 15 be permitted by the state of the prior art and the scope of the appended claims.

I claim:

1. In a one-piece closure cap, a top portion, an internally threaded skirt portion and a pilot member arranged inwardly of the skirt portion, said pilot member being hollow and depending from the top portion and having smooth inner and outer surfaces and terminating at its bottom in substantially the same plane as the bottom of said skirt portion, said pilot member having a top inner surface arranged below said top portion of the cap. 5

2. In a one-piece closure cap, a top portion, an internally threaded skirt portion, and a pilot member concentric with and arranged inwardly of the skirt portion, said pilot member being hollow and depending from the top portion and having smooth unthreaded inner and outer surfaces. 10 15
